COMB AND CLEANER COMBINATION

Henry Singer, Honolulu, Territory of Hawaii, assignor of one-half to John Henry Merrill, Honolulu, Territory of Hawaii

Application November 21, 1938, Serial No. 241,681

2 Claims. (Cl. 132—28)

My invention relates to a comb and cleaner combination and has as one of the principal objects thereof the provision of a comb equipped with means coacting with a cleaner for facilitating the cleaning of the comb.

Another object of my invention is to provide a comb and cleaner combination which is simple in construction, durable in use, efficient in operation and economical in manufacture.

10 Other objects and advantages will be apparent from the following description, appended claims and annexed drawing.

Referring to the drawing wherein like reference characters designate like parts throughout the 15 several views:

Figure 1 is a side elevation of a comb and cleaner combination constructed in accordance with my invention.

Figure 2 is a side elevation of the comb detached from the cleaner.

20 Figure 3 is a side elevation of the cleaner detached from the comb.

Figure 4 is a sectional view taken on the line 4—4 of Figure 1 and illustrating the comb and 25 cleaner in assembled condition for effecting a cleaning of the comb.

In practicing my invention, I provide a comb 5 formed with a lengthwise extending rib 6 provided with equally spaced teeth 7 including end teeth 8 and 9. The end tooth 8 has fashioned thereto a handle 10 integrally connected to the rib 6. The rib 6 is fashioned with teethwise extending sections 11 having oppositely disposed angular exposed faces 12 between the teeth. The oppositely 30 disposed faces of each section 11 converges towards the outer ends of the teeth for a purpose herein made apparent.

A comb cleaner 15 is associated with the comb 5 for removing foreign matter and the like from 35 between the teeth of the comb and comprises a relatively wide lengthwise extending rib 16 provided with spaced teeth 17 of a width adapted to yieldably fit between the teeth 7 of the comb. The teeth 17 include end teeth 18 formed with 40 offset sections 19 spaced from the adjacent lengthwise extending edge of the rib 16 and coact with the outer faces of the teeth 8 and 9 of the comb whereby to guide the cleaner relative to the comb to facilitate cleaning of the latter.

45 The device 15 is constructed of relatively soft

material, for instance rubber, and has the teeth 17 thereof positioned between the teeth 7 of the comb with the offset sections 19 engaging the outer faces of the teeth 8 whereby to provide a 5 guide for the cleaner upon relative movement of the latter and comb.

When the teeth 17 of the cleaner are moved towards the sections 11 and in angular relation to the teeth of the comb, a wiping action will be 10 had which effects a cleaning of the teeth and faces 12 of the comb 5.

The cleaner 15 is fashioned with a handle 20 integrally connected to the rib 16 as clearly illustrated in Figure 3 of the drawings whereby 15 said handle may be grasped in one hand with the handle 10 of the comb in the other hand as illustrated in Figure 1 of the drawing for effecting operation of the combination.

What I claim is:

1. In combination, a comb formed with a 20 lengthwise extending rib provided with spaced teeth, said rib having teethwise extending sections fashioned with angular exposed faces between said teeth, and a cleaner disposed in angular and sliding engagement with said comb and 25 formed with a rib juxtaposed in relation to said first mentioned rib, said rib of said cleaner provided with spaced teeth of a number and width to snugly fit between the teeth of the comb and 30 engage the faces of the sections therebetween to effect cleaning of the teeth and sections of said comb upon relative sliding movement of said comb and cleaner in a direction towards one of 35 said ribs to effect complete separation thereof.

2. In combination, a comb formed with a 40 lengthwise extending rib provided with spaced teeth, said rib having teethwise extending sections fashioned with angular exposed faces between said teeth, and a cleaner formed with a 45 rib provided with spaced teeth of a number and width to snugly fit between the teeth of the comb and engage the faces of the sections therebetween to effect cleaning of the teeth and sections of said comb upon relative movement of 45 said comb and cleaner in a direction to effect separation thereof, said comb and cleaner each provided with a handle to facilitate said relative sliding movement.

HENRY SINGER. 50
